(57) **CLAIM**

The ornamental design for a magnifier lanyard, as shown and described.

DESCRIPTION

1. Magnifier lanyard

1.1 : Perspective

1.2 : Perspective

1.3 : Front

1.4 : Back

1.5 : Left

1.6 : Right

1.7 : Top

1.8 : Bottom

1.9 : Perspective view shown in use with a magnifier

1.10 : Enlarged

The broken lines in fig. 1.9 depict the environmental structure of the magnifier lanyard that forms no part of the claimed design; fig. 1.10 is the enlarged view of the portion taken at line 10 in fig. 1.1; the dash-dot-dashed lines in the reproductions and the number “10” in fig. 1.1 are for the purpose of depicting the cut line of the enlarged view and form no part of the claimed design.
